(57) **CLAIM**

The ornamental design for a powerbars connector for a lighting system, as shown and described.

DESCRIPTION

FIG. 1 is a perspective view of a powerbars connector for a lighting system, showing my new design;

FIG. 2 is top plan view thereof;

FIG. 3 is a front elevational view thereof, the rear elevational view being a mirror image;

FIG. 4 is a right side elevational view thereof, the left side being a mirror image; and,

FIG. 5 is a bottom plan view thereof.

The broken lines shown in the drawings are included for the purpose of illustrating portions of the article that form no part of the claimed design.
